UNITED STATES PATENT OFFICE.

CHARLES NICHOLS, OF KANSAS CITY, MISSOURI.

AMUSEMENT APPARATUS.

1,069,629.

Specification of Letters Patent.

Patented Aug. 5, 1913.

Application filed August 6, 1907. Serial No. 387,282.

To all whom it may concern:

Be it known that I, CHARLES NICHOLS, a citizen of the United States, residing at Kansas City, in the county of Jackson and State of Missouri, have invented certain new and useful Improvements in Amusement Apparatus; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to an amusement apparatus, and more particularly to an apparatus for representing by means of a display board equipped with suitably disposed figures and lights, the progress of a base ball game or similar event which is taking place at a distance from the board.

It is the object of my invention to provide an apparatus of this class which will picture to the spectators each individual play made in the game, together with temporary and permanent recording parts, and means by which the standing of the opposing teams may be shown during the progress of the game.

In accomplishing this object I utilize a board or screen of suitable size, upon which is marked a representation of a base-ball diamond. Each of the base positions is provided with a device which may be illuminated or darkened at will, and each player's position is provided with a pair of similar devices, the latter being adapted to show different colors, and those indicating the bases being preferably of a third color, in order that the lights of each class may be readily distinguished from those of another class.

In the customary positions, adjacent to the diamond are indicated the benches for the players of the opposing teams, and extending from each bench to the "home plate", is a train of lighting devices which may be illuminated to indicate the travel of a player as he goes to bat; and extending around the diamond on the base lines are trains of similar devices which may be illuminated to indicate the travel of a runner around the bases.

Adjacent to the diamond is a list of the players; those on the same team being ar-

ranged one below the other in regular batting order, and those of the opposing team arranged in similar order adjacent to the first list, there being a lighting device separating the players in relative positions on the two lists to indicate the players who are at bat or on the bases, and a similar device over each list, by which is indicated the team at bat.

Below the batting order are three sets of lighting devices by which are indicated the "outs" made by the team at bat, and the balls and strikes record of the player at bat, each individual set of such devices being of a distinct color, in order that the information sought to be imparted thereby may more easily be grasped by the spectators.

Adjacent to the devices mentioned is an ordinary score board, and conveniently placed are other boards by means of which information regarding games between other teams in the same or other leagues may be given.

To add interest for the spectators, I provide a megaphone which projects through the board or screen, and through which the operator may call the plays. I further provide a gong which may be rung when a score is made, and a bell of different tone for indicating a hit when made by the batter.

While any suitable lighting devices may be used in connection with my apparatus, I prefer to utilize that shown in the drawings which I will, with the rest of my construction, now describe in detail. Reference being had to the accompanying drawings in which—

Figure I is a view in front elevation of an apparatus constructed according to my invention. Fig. II is a rear elevation of same, illustrating the light controlling mechanism.

Referring more in detail to the drawings—1 designates the board or screen upon the center of which is marked the representation of the base ball diamond, at each base position of which is a socket for an incandescent light bulb, the body of which socket projects through a perforation in board 1 and carries a switch mechanism by which current is turned into and from the bulb by an operator who stands behind the board. As before stated the light bulbs located at the base positions are of a distinct color, and on the drawings are given the character G to indicate green. Adjacent to the several base positions and in the custom-

ary positions in the field are figures to represent players, and adjacent to each of such figures is a pair of incandescent light bulbs having sockets mounted and connected as described in relation to the base lights, one bulb of each pair being white and the other red, as indicated by characters W and R.

5 $g^1-g^2-g^3-g^4$ designate incandescent lights which extend in a train between the bases, and, as these lights are utilized to indicate the travel of a runner between the bases, they are also preferably of a green color. Connected with each of such lights is a separate wiring which leads to a switch 10 $sg^1-sg^2-sg^3-sg^4$, such parts being so arranged that when either of the switches noted are turned on, the current will travel forwardly through the train to represent a runner traveling from one base to the next. 15 Extending from the players' benches B—B¹, are similar trains g^5-g^6 , which lead to the "home plate," and sg^5-sg^6 designates switches similar to those controlling the base line trains, and by which current may be 20 turned into said trains to give a representation of a batter traveling from the bench to the batting position.

At the outside of the foul lines and beyond the first and third base positions are the light bulbs R—R¹ by which may be indicated the fact that a foul has been struck by the batter, these bulbs being preferably colored red to more clearly distinguish them from other bulbs used in the apparatus.

30 The batting order and scoring parts have been previously mentioned, and are shown in the drawings where the names of the players of the local and opposing team are indicated on hangers, and a light bulb G⁴, 35 preferably of a green color is shown separating relative hangers of the opposing teams and a bulb W, is located above each of the lists, each of said bulbs being carried in a socket having a switch SG⁴ and SW, at the 40 back of the board by means of which the bulbs are illuminated and darkened.

Below the batting order are three sets of light bulbs the first containing three bulbs G⁶ of a green color to indicate outs and having the word "Outs" marked thereover; the second containing four bulbs R¹, of a red color to indicate balls called on the batter, and having the word "Balls" marked thereover; and the third containing three 50 white bulbs W¹, to indicate strikes called on the batter, and having the word "Strikes" marked thereover; each of the bulbs in the sets being carried in a suitable socket and having a switch SG⁵—SR¹—SW¹, at the 55 back of the board.

60 As the score boards shown are well known, I will not describe them in detail, as they individually form no part of my present invention.

65 At the rear of the board is located the

switch-board by which the apparatus is operated, and a part of the wiring for furnishing current for the lights; but as no invention is claimed on the individual parts, such as the switches or wiring, I will not describe same, as the mechanical parts are well known and the wiring such as could be properly arranged by a skillful electrician to connect the lighting parts previously mentioned. Besides these switching parts I provide the board with a gong P, by means of which the operator may indicate the scoring of a runner, an alarm O by which a hit made by the batter may be indicated, and a megaphone M, which projects through board 1 with its open end directed toward the spectators, and by which the operator may describe plays to aid the apparatus in giving a realistic and intelligent understanding of the play.

70 It will be noticed that the bulbs by which the plays relating directly to the team at bat, such as the base and batting bulbs are colored green, and the bulbs at the fielders' positions are colored white and red; this arrangement is made to distinguish the teams as far as possible, in order to obviate confusion in the plays.

75 To give a better understanding of the apparatus, the play for a half inning will be described: As previously mentioned the spectators are seated in front of the board, and the operator is stationed in its rear, where he receives reports from the game by telegraph or in any suitable way. Upon 80 being advised which team is at bat, the operator turns the switch which lights the bulb over the batting order for that team, which for illustration, we will take to be the local team here shown to be Kansas City; the next information received is that the play 85 is begun and the name of the man who has gone to bat, which is imparted to the spectators by lighting the bulb G⁴ opposite that player's name, by turning the switch sg⁴ for that particular light, and by starting the traveling light train g⁶, by turning the proper switch to indicate the travel of a player from the local bench to the batting position. Should the batter strike a ball or have a strike called on him by the umpire, one of the bulbs W¹ is illuminated. A second strike being called, the second white bulb is illuminated, and the third strike being made, the third bulb W¹ lighted; the catcher who has held the third strike is then shown to have made a put out, by having his white bulb illuminated, and the first green bulb G⁶ is then illuminated to indicate the out, and the other bulbs darkened, 90 with the exception of that at the head of the batting order. The next batter then has his light in the batting order turned on and the train G⁶ indicated his travel to the plate.

95 100 105 110 115 120 125 130

He hits the first ball outside the left field

foul line, and the red bulb R' is lit up to show the foul and the first bulb W¹ is lighted to show one strike; three balls are called successively and are shown by bulbs R¹; a 5 strike is called and shown by the second bulb W¹, and then a fourth ball is called which entitles the batter to his base; the fourth bulb R⁴ is illuminated, and the current turned into train g¹ to show the player 10 traveling to first; upon the train having run out at the base position, the base light G¹ is illuminated to indicate the runner's position. The ball and strike indicating bulbs are then 15 darkened; the bulb G⁴ opposite the next batter is illuminated and the train g⁶ again operated to indicate the player going to bat. This player knocks the first ball to the short 20 stop, who makes an error in fielding it, allowing the player at first to go to second and the batter to reach first; to represent this 25 play, the red bulb adjacent to the short stop position is illuminated to indicate his error, the trains g² and g¹ are operated to indicate the travel of the played from first to second, and the batter to first, and the base 30 bulbs G¹ and G² lighted to indicate the positions of the men on the bases. Another player then goes to bat and hits to center 35 for one base, the small bell ringing once to indicate a base hit, the train g¹ and base light G¹ operating as before; the man at second scores, and the man previously on first, takes second on the hit, trains g², g³, and g⁴ operating to show their travel, and 40 the gong ringing to indicate the score; the bulb opposite the scorer's name on the batting order being extinguished to indicate his retirement from the play. Another batter is then up, who hits a ball to the second baseman, who fields it to the short stop who 45 has covered the second base and the runner who has been forced off of first is out at second; the second baseman's white light being illuminated to indicate that he has fielded

the ball, and the short stop's white bulb being illuminated to indicate that he has aided in the play; the trains g¹, g² and g³ being illuminated to indicate the travel of the runners. As the man at second is out, his 50 batting order bulb is extinguished and another out shown at G⁵. The next batter up, flies out to the right fielder whose white light is illuminated to show the play. The side having made three outs all of the lights are extinguished, the bulb over the opponents' 55 batting order illuminated and the process repeated as described.

Having thus described my invention, what I claim as new therein, and desire to secure by Letters-Patent is—

1. An amusement apparatus comprising a background suitably marked to represent a base ball diamond, lighting devices at the base positions, and on the lines connecting said base positions, and means for illuminating said devices to show a train of light traveling between the base positions.

2. An amusement apparatus comprising a background bearing a representation of a base ball diamond, lighting devices extending between the base positions, and means for separately operating the devices between the different base positions to illuminate and darken each set independently of the others.

3. An amusement apparatus comprising a background bearing a representation of a base ball diamond, showing players' positions and benches, a series of lighting devices leading from each bench to the batting position, and means for turning current into each of said series for the purpose set forth.

In testimony whereof I affix my signature in presence of two witnesses.

CHARLES NICHOLS.
